DESIGN FOR A HANDLE FOR AN AUTOMOBILE SPOTLIGHT

Nils A. Tornblom, Chicago, Ill., assignor to Appleton Electric Company, a corporation of Illinois

Application December 21, 1936, Serial No. 66,676

Term of patent 7 years

To all whom it may concern:

Be it known that I, Nils A. Tornblom, a citizen of the United States, residing in Chicago, in the county of Cook and State of Illinois, have invented a new, original, and ornamental Design for a Handle for an Automobile Spotlight, of which the following is a specification, reference being had to the accompanying drawing, forming part thereof.

Figure 1 of the drawing is a top view of a handle embodying my design; and Figs. 2 and 3 are elevational views showing opposite sides of the handle.

I claim:

The ornamental design for a handle for an automobile spotlight, as shown.

NILS A. TORNBLOM.
